TAPE SUSPENSION FOR WINDOW SASH AND THE LIKE

Filed Dec. 29, 1928

INVENTOR.
SAMUEL ROSENBERG,
BY
H. Woodward

ATTORNEY.

UNITED STATES PATENT OFFICE

SAMUEL ROSENBERG, OF NEW YORK, N. Y.

TAPE SUSPENSION FOR WINDOW SASH AND THE LIKE

Application filed December 29, 1928. Serial No. 329,251.

The invention has for an object to effect improvements in the hanging of window sash and the like by means of metal tapes, and particularly to enable the embodiment of means to this end in such manner that the use of metal tape for this purpose may be effected economically and at a cost comparing favorably with the use of woven fiber cord or chain such as have heretofore been generally used. It is a special aim to provide a construction and arrangement adapted to enable the hanging of a sash on metal tape where the sash and frame are the same as ordinarily used with cord or chain. Particularly, it is sought to obviate the need for special tools in equipping a sash with a tape suspension, utilizing the ordinary sash weight.

An important aim of the invention is to enable the use of metal tape in suspension of sash upon a pulley with counter weight in such manner that displacement of the tape from the pulley will be prevented, as well as twisting of the tape and other derangements obviated. A further important object is to minimize wear of the tape and also lessen shocks thereto incident to abrupt stoppage of a sash at completion of closing or opening movements.

Additional objects, advantages and features of invention reside in the construction, arrangement and combination of parts as will be more readily understood from the following description and accompanying drawings, wherein,

Figure 1 is a fragmentary vertical section of a window frame and sash on which my invention is shown incorporated.

Figure 2 is a detail cross section of the pulley and tape.

Figure 3 is a detail section of the pulley and tape.

Figure 4 is a detail of the weight suspension.

Figure 5 is a detail of the eye guard for the weight detached.

Figure 6 is a view of the tape tie device in initial form.

There is illustrated a sash 15 which may be of any usual construction although in

the present instance the stile has been mortised as heretofore usual for the attachment of a simple braided fiber cord. That is to say, a groove 17 is formed in the edge of the sash stile at the upper part, and a distance below the groove a bored recess 18 open on the side of the stile is formed connected with the groove by a bored passage 19 of smaller diameter than the recess 18. The sash is hung in a frame 20 which at its upper part is suitably mortised at 21 as customary, to receive the common pulley assembly. In the mortise 21 there is located my improved pulley or sheave 22, which consists of a stamping or casting having two cheek plates 23 between which there is mounted the pulley wheel 24, which in the present instance is formed with a channelled periphery, the bottom of the channel in the pulley being flat, and the flanges 25 thus formed at the sides being much higher than the thickness of the tape which is to be used to suspend the sash. The plates 23 are formed integrally with a mounting plate 26 at right angles to them and of conventional form, apertured to receive fastening screws by which the pulley is secured to the frame 20. The plates extend above the wheel, and engaged through the upwardly extended parts of the plates diametrically above the pulley there is a pintle 27 on which a pilot roller 28 is mounted of a diameter to extend into the groove of the wheel a distance and of a length to fit loosely between the flanges of the wheel.

Over the pulley and under the pilot roller 28 there is laid a tape 29 of suitable thin flexible metal, the ends of the tape being connected respectively to the sash and to a weight 30 of conventional form. The tape is preferably of bronze or other suitable non-corrodible metal, and for common use it is made in a width of $\frac{15}{16}$ to $\frac{3}{8}$ inch, and about 26 gauge in thickness, although these proportions may be varied to suit the requirements.

Where the tape is connected to the weight it is run through the loop of the P-shaped manual tie 37 and the eye of the weight and then bent to form a bight 32 in which is laid a guard 33. The latter is a channel-form steel

member bent medially to substantially a **U**-shape initially, and manually bendable further to bring its ends together so as to form a substantially pear-shaped eye. The flanges 34 of the guard are located at its outer sides and spaced so as to receive the tape snugly therebetween. The extremity of the tape is next again inserted through the **P**-shaped tie 31 in a direction the reverse of that in which it was first inserted, close upon that part of the tape already engaged therein, but at the side next the stem portion 35 of the tie, and the extremity of the tape on this second insertion in the tie is allowed to project a short distance. It is then bent sharply backward upon the overlying part of the tie. The stem part of the tie is finally bent down upon the inturned end of the tape so that it is held securely against loosening. The manual bending of the tie upon the tape parts will afford security, but the completed tie may be further flattened and secured by being squeezed in a pair of pliers, or by being struck by a hammer while laid on a flat surface.

25 The tape is engaged with the sash at 18 in any approved manner. It will be noted that the periphery of the pulley wheel lies with the bottom of the groove at the front side immediately outward of the plane of the 30 plate 26. The roller 28 stops short of the bottom of the groove just sufficient to permit the tape 29 to pass thereunder as described. It nevertheless extends into the groove a substantial distance, so that the tape is held 35 with a considerable extent of flange 25 extending above and forwardly of the tape, throughout the upper part of the pulley. Owing to the rigidity of the tape to flexure in directions transverse to its major trans- 40 verse axis, any tendency of the tape to ride upon the flanges 25 is firmly opposed as long as the tape is held under the roller 28, because the tape itself so opposes bending toward the sides of the sheave that it cannot get suffi- 45 ciently out of line to ride on the flanges 25.

I claim:

A sash suspension comprising a case adapted to be mounted in a window frame, and including a vertical face plate, cheek plates 50 extended inwardly therefrom, a wheel mounted between the cheek plates having a flat-bottomed groove and having its periphery closely adjacent and outward of the plane of said plate at the front side of the roller, and a 55 pilot roller of cylindrical form revolvably mounted between the said cheek plates at the upper side of the wheel, and set in the groove a substantial distance adapted to lie close to a tape in the groove, and close to the 60 sides of the groove, and a tape closely confined in the bottom of the groove under the roller.

In testimony whereof I affix my signature.
